UNITED STATES PATENT OFFICE

2,141,999

KNITTED FABRIC AND METHOD OF
MAKING SAME

James McNamee, Ballston Spa, N. Y.

Application January 31, 1938, Serial No. 187,994

10 Claims. (Cl. 66—198)

This invention relates to weft knit fabric and the method of making same, and more particularly to the obtaining of an inelastic knit fabric. One of the disadvantages of ordinary weft knit fabric is that it is elastic and therefore not practical for certain uses, such for instance as for shirts or other outerwear. It is an object of this invention to produce a substantially inelastic weft knit fabric by the use of a spring beard needle knitting machine, preferably a circular united 5

in my method of procedure is accomplished. The yarn is then pushed up under the beards 14 of the deflected needles and in back of the non-deflected needles 13 till the yarn lies in a straight line at the top 15 of the bends in the needles. It will lie under and over successive needles, as shown in Fig. 4. It will be observed that the yarn is still taut and not slack as is the case in a yarn fed through a stitch wheel. This tautness is not lost through the rest of the manipulation and therefore the stitches are extraordinarily tight. As these tight stitches 25 and the bights 31 connecting them are part of the entire cloth and not only connect the wales together but also connect the courses together, there is only a minimum of expansibility in the fabric, both in coursewise and walewise directions.

As already mentioned, my new method can be carried out and my fabric produced on a circular spring beard needle machine, i. e., a spring beard needle machine where wheels are used to cause the manipulations of the yarn and needles. I shall now describe one feed of such a machine. Considered in the direction of movement of the needles, the first wheel is the interlacing wheel 16. This meshes with the needles and is rotated by them, and in such rotation presses alternate needles 12 radially inward out of line owing to the usual plugs between every alternate pair of blades (not shown) in the wheel. This wheel is mounted at an angle with the horizontal outside the needle circle, as usual. The tight or binding yarn 11 is presented between the two lines of needles created by the interlacing wheel, the yarn preferably coming from a tension device (not shown) which keeps it taut. It will be noted that in this way the yarn is laid in in a straight line or single arc, as distinguished from being pressed in between every pair of needles into a slack loop. This interlacing wheel is located at such an elevation and proximity to the needle circle that the deflection is sufficient to have the yarn lie between the two circles of needles below the points of the beards of the needles. As soon as the interlacing wheel lets go of the needles they tend to return to a straight line and the yarn is interlaced in back and in front of alternate needles as tightly as possible. This resumption of single line position by the needles does not cause the drawing of additional yarn, and I have found by test that a given length of yarn fed to the needles by the above method covers twice as many needles as it is possible to cover by the same length of yarn fed to a spring beard needle machine. In the meantime the usual cloth wheel 17 has been pushing the old loops further down the needles. Since the length of yarn was in the first instance laid in a straight line in the machine, it follows that this binding yarn is as short as is practically possible.

The next step is to raise the binding yarn 11 to the very tops of the needles, this being done by a lifting wheel 18 outside the needle circle which precedes the regular stitch wheel for the body yarn. This lifting wheel raises the binding yarn to the very tops 15 of the needles where it is under the hook of every other needle and lies straight across on the tops of the intervening needles 13, again assuming practically a straight line. This gets the tight yarn out of the way of the blades of the stitch wheel for the regular yarn and it is now possible to feed this regular yarn 22 by its ordinary stitch wheel 19, which thereafter presses the regular stitches between the needles 75 and raises them up under the beards 14 in the

usual manner. Without the lifting wheel 18 it would be impossible to draw the loops of the regular yarn 22. The stitches are then cast off by the regular mechanism, which includes a main presser 20, an inside lander wheel 21 and a cast-off wheel 23. In this way the body or regular yarn knits a stitch 24 on every needle and the tight or binding yarn knits a stitch 25 on every other needle. The bights of binding yarn between the tight stitches coming off the alternate needles are very short and in conjunction with the very tight stitches of this yarn stretching across the intervening stitches of the regular yarn, combine the whole fabric together in inelastic form.

To keep my novel fabric very tight, there must be some sort of stitch wedged between each two tight stitches in the final fabric. This may be done by having the body yarn knit on every needle with a common stitch wheel, as described above, or by having a yarn knit only on the intervening needles 13 so that the stitches of this body yarn 22 would lie between the stitches of the binding yarn 11, which itself is knit on alternate needles 12 (Fig. 6). In this latter form it is possible to make tight stitches of both yarns by the use of two interlacing wheels such as above described, instead of one interlacing wheel and one stitch wheel.

The fabric may be made and the method carried out on either a multi-feed or a single feed machine. Thus on a single feed machine successive courses may make tight stitches on the same needles or may alternate with the tight stitches on the alternate needles in one course and on the intervening needles on the next course. As already mentioned, it is possible to make one form of this fabric out of a single yarn, and this can be done on a single feed machine by having an interlacing wheel for the binding yarn rather than a regular stitch wheel. In this case, in order to obtain the stitches between two adjoining tight stitches in a course, it is necessary that the machine have an odd number of needles in it. Thus the tight stitch in one wale will come first in one wale and then the next wale on the succeeding courses. When using only one yarn at a feed, there must be a cut presser at that feed to prevent casting off at those needles where the yarn was above the top of the needle. This cut presser thus serves to prevent complete casting off of the fabric due to lack of loops under the beards.

On a multi-feed machine it will be obvious that any number of feeds having the combination of an interlacing wheel for the binding yarn and a stitch wheel for the body yarn can be provided. In this case the setting or meshing of the wheels with the needles determines whether a tight stitch in the two courses will come in the same wale or the adjoining wale. If the two interlacing wheels of the two adjacent feeds are set to deflect the same needles, the tight stitches made at the two feeds will occur in the same wale. If the two interlacing wheels press the needles in alternation, then the tight stitches will be in alternate wales. It will be obvious that more than two feeds can be used by following the same principle, obtaining any pattern variation that is desired. If the machine has an odd number of needles and the desired form of fabric is that in which tight stitches are in alternate wales in adjacent courses throughout the fabric, then the machine should have an odd number of feeds to carry the alternation through from one revolu-

tion of the needle cylinder to the next. With an even number of needles in the cylinder and employing two or more even number of feeds on the machine, the alternation of wales in which the tight stitches are present would be accomplished by meshing the interlacing wheels of adjacent feeds to operate on different needles.

Another possible modification in my novel fabric is to intercalate courses 26 of plain knitting or courses of other types of knitting with courses 27 of the novel stitch construction above described. Thus in Fig. 2 has been shown an alternation of one course of my novel stitch formation with a single course of plain knitting. 15 There is no appreciable loss in firmness and non-extensibility of the fabric due to the intercalation of the plain single courses. The bights 32 of the tight yarn and the tight stitches 25 are no less tight.

20 Not only does my fabric hold firmly and tightly together, but the appearance of the fabric is novel and attractive. In Figs. 7, 8 and 9 the attractive and novel appearances of the three forms of my fabric are shown. This fabric possesses certain characteristic attractive qualities 25 of balance and depth, in addition to the inelasticity and firmness.

In the ordinary knitted fabric there is greater extensibility in a coursewise direction than in a walewise direction. In my novel fabric the wedging of stitches between each two adjoining tight stitches serves to bring the extensibility in the two directions into balance, and the filling, combined with the tight stitches, therefore produces a fabric which is substantially inelastic in 35 both coursewise and walewise directions. I also find that the fabric is substantially inelastic to the same extent and degree in diagonal directions. The filling, bulk or body is of course best obtained by knitting two yarns in each course, so that at least certain stitches have two yarns in them. It is preferable, when knitting with two yarns, to use yarns of the same size. The preferred embodiment of my invention is the 40 form in which the tight stitches are in staggered wales and the bulk or filling includes plain stitches of a second yarn. While both Figs. 1 and 2 show this preferred form, from the point of view of inelasticity and balance the form of Fig. 1 is preferable to that of Fig. 2. The embodiment of Fig. 2 is slightly more economical of yarn 45 than the embodiment of Fig. 1.

The pertinent elements of the usual spring beard needle circular machine having been described, the manipulation of the machine to produce the novel fabric shown in Fig. 1, where there are no intervening plain courses and the tight stitches 25 occur on alternate needles 12 in successive courses, will now be described. I will describe only one feed. The usual cloth wheel 17 inside the needle circle pushes the knitted cloth down until the loops on the needles are near the base of the needles, all in the usual manner. With the cloth in this position and the needles 55 entirely clear of loops except for these loops at the base, the interlacing wheel 16 presses every other needle 12 radially inward and the binding yarn 11 is laid in a straight line between the two circles of needles below the points of the beards 60 14. As soon as the needles are released, the lifting wheel 18, which follows the interlacing wheel 16, immediately starts lifting the binding yarn 11 up to the tops 15 of the needles until it is 65 under the beards of the alternate needles 12 and 70 on top of the intervening needles 13. Next the 75

regular stitch wheel 19 feeds the body yarn 22 in the usual manner to every needle, taking slack or bights 28 of yarn between each two needles. Thereafter the needles encounter a presser 20 which closes the beards, while from the inside of 5 the needle circle the lander wheel 21 works the cloth upward over the points of the beards, while they are closed. The needles then pass beyond the presser and encounter the castoff wheel 23 which, lying on the inside of the circle, casts off 10 the fabric forming a new course of stitches, as above described. In this final operation a goodly portion of the bight of the tight yarn is absorbed in the formation of the tight stitch. The final bight 31 exerts a strong pull on the adjoining 15 tight stitches, holding them as close together as possible.

When in a multi-feed machine, consecutive interlacing wheels work on different needles—there being an even number of needles in the 20 cylinder—the result is the same as a single feed working with an odd number of needles in the cylinder. When the tight stitches in consecutive courses occur in alternate wales, as mentioned, for example, in the preceding sentence, the tight 25 stitch of one course will be cast off over the plain stitch of the succeeding course. In this way the so-called "open ends" 29 of each common stitch 24 are completely and tightly closed by the tight stitch. It is pointed out that although in 30 the method of manufacture it might be said the binding yarn is floated across alternate needles—instead of having a float thread with a normal length of float and a given number of ordinary stitches in the course—my fabric has a tight 35 thread from which a given number of exceedingly tight stitches have been formed substantially from what might otherwise be called the float portions. In other words, the thread is so excessively tight that it has composite stitches 40 tighter than have heretofore been possible, the fabric has almost no elasticity left in it and the stitches are so small that they have practically no elasticity in them.

I find that this knitted fabric has the appearance 45 of woven goods and therefore can be used without sales resistance where woven goods have heretofore been used. The fabric has remarkable depth, tightness and balance, all inherent in its construction. It is free from the twist which 50 is sometimes found in knitted cloth, and not only are its knitted wales unapparent, thereby giving it the appearance of woven goods, but its body, depth, firmness and balance give it the feel of woven goods.

55 Other modifications which do not depart from the scope of my invention will occur to those skilled in the art.

What I claim is:

1. A weft knit fabric containing a plurality of 60 courses each knit of two yarns, one yarn being knit at least in every alternate wale of the fabric and the other yarn only in the intervening wales in the same course, the stitches of the first-mentioned yarn being normal tight stitches and the 65 length of the second yarn in such a course being not more than half that of the first yarn, whereby the fabric is held compact in a substantially inelastic condition.

2. A knitted fabric in which two weft yarns 70 are knit in each course, at least one of said yarns being knit only in alternate wales and the other with as great or greater frequency, the stitches of at least one yarn being knit substantially twice 75 as tight as a normal tight stitch so as to draw

and hold the wales together, eliminating substantially all the elasticity of the fabric.

3. A fabric containing a plurality of successive courses each knit of a body yarn and a binding yarn, the body yarn being formed into normal tight stitches in every wale in a course, and the binding yarn being floated across intervening wales and knit in alternate wales, the stitches of the binding yarn being not more than half the size of the stitches of the other yarn, whereby the wales are held together and the fabric is substantially inelastic.

4. A weft knit plain fabric containing a body yarn and a binding yarn in each course, the body yarn being formed into normal tight stitches in a plurality of successive wales and successive courses, in combination with binding yarn formed into stitches in spaced single wales only, the length of the binding yarn in a plurality of wales being less than half the corresponding length of the body yarn, whereby the fabric is made substantially inelastic.

5. A weft knit plain fabric containing at least a body yarn and a binding yarn in each course, the body yarn being formed into normal tight stitches in every wale in a plurality of successive courses and the binding yarn being formed into stitches in spaced wales only, the length of the binding yarn in a plurality of wales being less than half the corresponding length of the body yarn, whereby the fabric is made inelastic.

6. A method of knitting fabric on a spring beard needle machine, comprising the steps of interlacing a yarn between the shanks of alternate needles, raising it to the tops of the needles under the beard of one and on top of the next needle while maintaining the yarn taut, then feeding a second yarn by means of a stitch wheel and knitting off both yarns, whereby the first yarn holds the wales and courses together in substantially inelastic condition.

7. A method of knitting fabric on a spring beard needle machine, comprising the steps of

deflecting alternate needles out of line, laying a yarn taut in between the two lines of needles thus formed, bringing the needles all back into one line and raising the yarn to the tops of the needles under the beard of one needle and on top of the next in such manner that the yarn will lie in a substantially straight line, feeding a second yarn to all the needles by means of a stitch wheel and then knitting off both yarns, whereby the first yarn will hold the fabric together, making it inelastic.

8. A method of knitting fabric on a spring beard needle machine, comprising the steps of forming stitches on alternate needles by interlacing a yarn between the shanks of alternate needles while maintaining it taut, raising it under the beards of alternate needles till it lies substantially straight over and under the tops of the needles, knitting off said yarn and producing other stitches to lie wedged between each two such adjoining tight stitches, whereby a substantially inelastic fabric is produced.

9. A method of knitting fabric on a spring beard needle machine, comprising the steps of interlacing a binding yarn between the shanks of alternate needles, raising it under the beards of alternate needles till it lies substantially straight over and under the tops of the needles, feeding a body yarn to all the needles with at least the normal amount of slack and then knitting off both yarns simultaneously, whereby a substantially inelastic fabric is produced.

10. A weft knit plain fabric containing a body yarn and a binding yarn in each of a plurality of successive courses, the body yarn being formed into normal tight stitches in every wale in said courses, and the binding yarn being formed into stitches in alternate single wales and floated in the intervening wales, the binding yarn in a course being not more than half the length of the corresponding body yarn, whereby the fabric is made substantially inelastic.

JAMES McNAMEE.
